UNITED STATES PATENT OFFICE.

LAWRENCE R. LIBBY, OF HARTFORD, CONNECTICUT.

SECTIONAL BOILER.

SPECIFICATION forming part of Letters Patent No. 727,814, dated May 12, 1903.

Application filed April 7, 1902. Serial No. 101,629. (No model.)

To all whom it may concern:

Be it known that I, LAWRENCE R. LIBBY, a citizen of the United States of America, residing at Hartford, in the county of Hartford and State of Connecticut, have invented certain new and useful Improvements in Sectional Boilers for Steam or Hot Water, of which the following is a specification.

My invention has for its object to produce a boiler of the class specified having features of novelty and advantage.

In the drawings, Figure 1 is a perspective view of my boiler having some parts broken away to show construction. Fig. 2 is a perspective view of the boiler-front. Fig. 3 is in part a rear view of the boiler-front shown in Fig. 2 and in part a sectional view of the boiler-sections looking toward the front. Fig. 4 is a perspective view of the boiler, showing both vertical and horizontal sections.

This boiler is adapted for use either as a steam or hot-water boiler, or as both. It has the usual fire-box A, the steam-drum B, the hot-water drum C, and the smoke-box E. The outer side walls D D are hollow, forming a water-jacket. The inner faces of these side walls are corrugated, as shown at d, to allow for expansion and contraction without warping or destroying the jackets. My boiler-sections G H K extend continuously from front to rear, each having the direct flues g' h' k' communicating with the fire-box at the rear, as at g² h² k², and the return-flues g h k opening at the rear into the smoke-box E. The

number of the boiler-sections to be used can of course be varied, three being shown in the drawings. Between these sections and between the outer sections and the side walls there are clear spaces g³ g⁴ h³ k³, which extend for the full height of the sections, as clearly shown in Figs. 1 and 3. At the top the sections are bulged or enlarged on each side, as at m, so that each section very nearly but not quite contacts with the other and the outer sections with the sides D D. It will be seen that the steam-drum B is connected to each section and to the sides D D by rigid, inflexible, and steam-tight joints. It has been found in using other sectional furnaces where means are not provided for removing the soot, scale, &c., that after a time they collect and settle between the sections, spread-

ing them apart and finally cracking and breaking out the connections between the steam-drum and the boiler-sections. By my construction I effectually dispose of these objections to the present type of sectional boilers, inasmuch as any soot or scale will drop into the fire-box. I propose to caulk the openings between the sections at the top with a yielding fireproof material, as the asbestos rope R, and then to cover the whole boiler with a plastic material, such as asbestos. In order to support this plastic material on the side of the furnace, I roughen the outer sides, as by ribs or a gridwork, as shown at N in Fig. 1.

The several sections G H K and the side walls D D of the boiler fit into recesses G' H' of an independent cast front P, being supported at p, these recesses forming a connection between the flues g' g' and k' k'. After the side walls and the boiler-sections have been assembled in the front P the joints are sealed with cement or some suitable material. The flames and heat pass in the direction of the arrows to the front of each section, up into the front of the upper sections, and thence toward the rear and out into the smoke-box E. In order to insure the flame moving from the lower flue to the upper flue in the same section, I provide flanges M, which are formed preferably integral with the front P and extend rearwardly a sufficient distance to just enter the spaces g³ g⁴ h³ k³ between the several sections, thus effectually cutting off one set of flues from the other.

The construction herein described and shown has many advantages over all sectional boilers which are now in use. It has been found that the life of the present boilers of this class is, at the outside, not more than six years, it being found that the continual expansion and contraction of the sections will in this time break the steam-joints connecting the several sections with the steam-drum, this being due to the fact that no allowance is made for the expansion. In my boiler this difficulty is obviated by the construction which has been herein described. Also in permitting the fire to shine on the sections to their full height I get a considerably-larger capacity with a lesser number of sections, and consequently at a greatly-reduced cost, than is possible with any of the types of sectional

boilers now in use. The whole construction of my device is extremely simple and efficient.

I claim as my improvement—

1. In a steam or hot-water boiler of the kind described, a series of sections extending from front to back of the boiler and arranged side by side, a direct and return flue wholly contained in each section, and a front for said boiler having independent chambers into which the direct and return flues open.

2. In a steam or hot-water boiler of the kind described, a series of independent sections extending from front to back of the boiler and arranged side by side, a direct and return flue wholly contained in each section, and the water-front for said boiler having independent chambers into which the direct and return flues open.

3. A boiler composed of sections extending from front to back thereof, each section being formed in a single piece and provided with a complete set of flues.

4. A steam or hot-water boiler of the kind described, made of a series of sections complete in themselves and extending from front to back of the boiler, each section having a direct and return flue, and a front for said boiler containing independent chambers into which the flues in each section open.

5. A steam or hot-water boiler of the kind described, comprising hollow side walls having their inner surfaces corrugated, and a series of independent sections arranged side by side between the side walls, said sections at the top and back approximately contacting with one another and with the side walls, but separated from one another and from the side walls by a substantial space from bottom to top, substantially as described.

6. A steam or hot-water boiler of the kind described, comprising hollow side walls for water-heating spaces, the inner faces of said side walls being corrugated, and a series of flue-containing independent boiler-sections each being complete in itself arranged side by side between the side walls, said sections at the top adapted approximately to contact with one another and with the side walls, but separated from one another and from the side walls by a substantial space from bottom to top.

7. A steam or hot-water boiler of the kind described, comprising a series of sections extending from front to back of the boiler, each section being separated from the other by a substantial space; a direct and return flue in each section; a front having chambers corre-

sponding in number to the number of sections and registering with the flue-openings in the front of each section; and flanges on said front adapted to enter the spaces between the sections, all substantially as described and for the purposes set forth.

8. In combination in a steam or hot-water boiler of the kind described; the fire-box; the side walls having corrugated inner surfaces and roughened outer surfaces; a series of sections arranged lengthwise of the boiler and located between the side walls; a front having chambers and flanges; and a direct flue in each section communicating with the fire-box and extending toward the front of the section and opening into the chamber in the front; and a return - flue opening into the chamber at the front and extending to the rear of the section discharging into the smoke-box.

9. A boiler composed of sections extending from front to back thereof, each section being made in one piece complete in itself as to its fire and water spaces, substantially as described.

10. In a steam or hot-water boiler of the kind described in combination the hollow side walls, the series of independent flue-containing sections extending from front to rear of said boiler, and a front recessed to receive and support the front ends of the several sections, all substantially as described.

11. In a steam or hot-water boiler of the kind described in combination the side walls, the independent flue-containing sections each complete in itself and located adjacent to but not in contact with one another and with the side walls, the spaces between the sections being in communication with the fire-box, all substantially as described.

12. In a steam or hot-water boiler of the kind described in combination the independent sections each of which is a complete boiler in itself, and the hollow side walls extending from front to back and arranged side by side, said sections at the top and back approximately contacting with one another and with the side walls, and a yielding fireproof backing closing the openings between the sections and between the sections and the side walls, substantially as described.

In testimony whereof I affix my signature in presence of two witnesses.

LAWRENCE R. LIBBY.
